UNITED STATES PATENT OFFICE.

HARRY RANDOLPH VAN DEVENTER, OF SUMTER, SOUTH CAROLINA, ASSIGNOR, BY MESNE ASSIGNMENTS, TO SPLITDORF ELECTRICAL COMPANY, OF NEWARK, NEW JERSEY, A CORPORATION OF NEW JERSEY.

ARMATURE FOR IGNITION-DYNAMOS.

1,252,514.

Specification of Letters Patent.

Patented Jan. 8, 1918.

Application filed December 2, 1914. Serial No. 875,104.

To all whom it may concern:

Be it known that I, HARRY RANDOLPH VAN DEVENTER, a citizen of the United States, residing at Sumter, in the county of ⁵ Sumter and State of South Carolina, have invented certain new and useful Improvements in Armatures for Ignition-DYNAMOS, of which the following is a specification, reference being had to the accompanying ¹⁰ drawing.

My invention relates to dynamos for ignition purposes, and has for its object the provision on the armature of a collector ring that is simple in construction and adapted ¹⁵ to be stamped and formed from sheet metal and securely held in place by stamped pieces of insulation.

A further object is to provide a collector ring assembly in which a minimum number ²⁰ of parts are used and the necessity for hand fitting is to a large extent eliminated.

Figure 1 is a view partly in section of a magneto generator, embodying my invention. Fig. 2 is a view partly in section of an ²⁵ armature head with the collector ring in place. Fig. 3 is a modification of Fig. 2. Like figures of reference denote the same parts wherever they are shown.

Heretofore, it has been customary to ³⁰ secure a piece of insulation to the armature head, this insulation carrying a plain ring, this ring being clamped in place by an outer insulating flange or being secured to the insulation in some suitable manner. In this ³⁵ construction, a suitable conductor is connected to the ring and brought through the end plate, from which it is insulated by a suitable bushing or thimble. Such a construction is open to several objections, such as the ⁴⁰ necessity of securing the insulation carrying the ring to the end plate, the necessity of a bushing through the end plate and the necessity of securing the ring to the insulation and the amount of hand fitting necessary. ⁴⁵ All of these objections are eliminated by my construction, the preferred form of which is as follows:

1 denotes a stub shaft having a shoulder indicated at 2, against which is placed one ⁵⁰ or more metallic washers 3, which form a support for the washer of insulating material 4, which fits tightly on the shaft and which is of the same diameter as the internal diameter of the collector ring 5 which is

placed over and against it, as shown. The ⁵⁵ hole through the collector ring for the shaft is of greater diameter than the shaft so that the collector ring is not in contact therewith, but is supported away from same by means of the insulation 4. ⁶⁰

Against the back of the cup-shaped collector ring is placed the insulating washer 6 and against this the armature end plate 7. The projecting end of the shaft is now upset or otherwise securely riveted over 7 as indicated at 8, whereby all of the foregoing parts are firmly secured together to form the structure shown in Fig. 2.

While I have described the shaft 1 as having a shoulder, it is obvious that the ⁷⁰ washers 2, 3 and 6 together with the head 7 may be simply pressed on the shaft, but the preferred construction is the employment of the shoulder 2 with the parts held together by the upset end 8. ⁷⁵

Fig. 3 shows the modified form of the arrangement shown in Fig. 2 in which the flange on the collector ring is omitted same being simply a flat perforated disk as shown in which case the contact brush 12 may be ⁸⁰ arranged to engage the disk horizontally as shown in Fig. 3 instead of vertically as shown in Fig. 1. Such an arrangement I deem within the scope of my invention.

To eliminate the necessity heretofore existing of bushing the end plate 7 and leading a wire therethrough to connect with the collector 5, I form an aperture in 7 adapted to accommodate a rearwardly extending tongue 9, which is preferably formed integral with ⁸⁵ the collector 5. The aperture in 7 is larger than 9 so the latter may pass without danger of contact, as 9 is rigid enough to be self-supporting. ⁹⁰

By reference to Fig. 1 showing the armature with collector ring in place, it will be evident that one end of the winding 10 is connected to the frame of the armature at 11 and the other end of the winding, to tongue 9 and that the circuit extends from the collector ring 5 to the brush 12 to the terminal 13 and from there, to any suitable spark producing device, the circuit returning from said ¹⁰⁰ sparking device being completed through the frame 14 of the magneto. ¹⁰⁵

It will be observed that there are no pins, screws, small insulating bushings or other members used in connection with this col-

lector ring assembly. Furthermore that the various parts are stamped and therefore of correct size in relation to each other, so that they are easily and accurately assembled 5 with a minimum of hand fitting.

And it will be understood that the magneto herein shown is merely for the sake of illustration and that my improved collector ring assembly may be employed in any other 10 form of magneto wherein a suitable terminal brush is supported in contact relation with said ring.

Having thus described my invention, I claim:--

- 15 1. An armature comprising a core and winding, an end plate secured to said core, a shaft secured to said end plate, and an insulated collector clamped to said shaft by said end plate.
- 20 2. An armature comprising a core and winding, an end plate secured to said core, a shaft secured to said end plate and an insulated collector clamped to said shaft by said end plate and having an inwardly projecting 25 integral tongue.
- 30 3. An armature comprising a core and winding, and an end plate secured to said core, a shaft secured to said end plate, a flanged collector surrounding said shaft, an insulated disk between said collector and

said end plate, a second insulating disk with in the flanged portion of said collector serving to position the same on said shaft, and means for clamping said disks and collector to said end plate, said means including a 35 shoulder on said shaft.

4. An armature comprising a core and winding, an end plate secured to said core, a shaft secured to said end plate, a collector ring surrounding said shaft, insulating 40 disks on each side of said ring, and means for clamping said shaft, collector ring, disks, and end plate together, said means including a shoulder on said shaft.

5. An armature shaft having a bearing 45 portion and a shouldered portion of less diameter than the bearing portion, a collector comprising a centrally apertured cup-shaped metallic member, insulating members on each side of said member, an end plate having a central aperture adapted to receive the shouldered portion of said shaft, and means whereby all of the foregoing elements are clamped together, substantially as described. 50

In testimony whereof I hereunto affix my 55 signature in the presence of two witnesses.

HARRY RANDOLPH VAN DEVENTER.
